B. J. LA MOTHE.
IRON BUILDING.

No. 11,809.

Patented Oct. 17, 1854.

UNITED STATES PATENT OFFICE.

BERNARD J. LA MOTHE, OF NEW YORK, N. Y.

IRON BUILDING.

Specification of Letters Patent No. 11,809, dated October 17, 1854.

To all whom it may concern:

Be it known that I, BERNARD JOACHIM LA MOTHE, of the city, county, and State of New York, have invented a new Mode of 5 Constructing Buildings Possessing Advantages in Security and Economy over Every other Known Mode of Construction; and I do declare that the following is a full and exact description thereof.

10 The nature of my invention is such that buildings of any form and for any use whatever can be constructed with much less material yet possessing far greater strength and tenacity throughout than by any other 15 known mode of construction, these objects being obtained from the nature of the material used and the peculiar manner of connecting the different parts.

To enable others skilled in the art of 20 constructing buildings to use and apply my invention I proceed to describe its construction and application, reference being had to the annexed drawings making a part of this specification in which:—

25 Figure 1, represents an internal side view. Fig. 2, a vertical transverse view. Fig. 3, a side view of a continuous beam. Fig. 4, a top horizontal view of said beam.

The foundation of my building is laid in 30 the ordinary manner with either stones, brick or any other suitable material. In said foundation are perpendicularly inserted and firmly secured sets of bands or plates of iron, steel or other metal. Each set consists of many such bands or plates strongly 35 riveted or screwed together at very short distances as represented at A A A, Figs. 1 and 2. In large structures the rivets or screws are in two or more rows near the 40 edges of the bands, and at a distance from each other not exceeding the diameter or thickness of the whole set of bands particularly when great strength or firmness in the structure would be required. These 45 bands thus riveted or screwed together in sets and firmly inserted in the foundation answer the same purpose that iron or stone pillars or wooden posts do in other buildings. At the proper height for the first floor 50 a number of the said perpendicular bands are carefully bent to a horizontal position as seen at B, B, Fig. 2, and riveted or screwed together at very short distances and form the beams or a part of the beams for 55 the same first floor as seen at C, C, Fig. 2. For the construction of the second story

the remaining perpendicular bands are carried up in precisely the same manner as for the first story as seen at D, D, Fig. 2, and screwed together at very short distances, 60 and at the required height for the second floor a further number of said bands are bent to a horizontal position and riveted or screwed together to form the beams or a portion of the beams for the said second 65 floor as seen at E, E, Fig. 2. The construction is thus continued to whatever height the building may be carried and the remaining perpendicular bands are then properly bent from all sides of the structure as seen 70 at F, F, Fig. 2, either in the form of arches or otherwise and riveted and screwed together to form the rafters of the roof as seen at G, G, Fig. 2.

The perpendicular sets are crossed between the doors and windows with other bands running in a horizontal direction and riveted to them as seen at H, H, Fig. 1. Moreover other bands in sets well riveted together may be laid with the edges vertical, 80 across every floor as seen at I, I, Figs. 1, and 2, and firmly attached to the horizontal sets, as seen at J, J, Fig. 2, and also to the perpendicular sets as K, K, Figs. 1 and 2, thus adding great strength and completing 85 the beams for the floors. Fig. 3, represents a side view of such sets and Fig. 4, a top or horizontal view of the same. Still further the last mentioned sets, in buildings of several contiguous apartments can and must be 90 extended from one apartment to the other well fastened to the perpendicular sets at each crossing of the internal or partition walls and thus every such set constitutes, as it were, a continuous beam, as represented in 95 Fig. 4, and extending through the whole building from one side to the other and strongly secured to the outer or main walls by means of a loop or otherwise by passing the ends of the bands between the perpendicular sets strongly riveted thereto or in any other manner equally adequate.

When the bands or plates cannot be conveniently used of sufficient length, so as to extend from the foundation to the top, or 105 from one side of the building to the other, the lengths of the sets can be carried to any extent without impairing their strength as shown in Fig. 4 at L, L.

The above relates to the frame or skeleton 110 of buildings. The finishing may be completed in accordance with the locality and

the uses intended. For, example; in a dwelling house, the spaces or distances between the perpendicular sets can be filled up with plates of metal, one forming the outer, and one forming the inner surface of the wall, and the space or vacuum between the two plates be filled up with some nonconducting substance, such as powdered charcoal, sawdust, ashes, &c., &c., and the internal surface plastered or papered as preferred.

The great security of this mode of construction is apparent. The frame being interwoven throughout as described, and with the identical material implanted in the foundation, it follows that every part is held immovable. At the same time the building has great lightness, and can be constructed at comparatively small cost.

20 Claim.

1. I claim as my invention and desire to secure by Letters Patent the construction of

the frame or skeleton of buildings with bands or plates of iron or steel or other metal riveted or screwed together in sets of several 25 parallel bands, the same extending from the foundation to the top of the structure, in lieu of columns, pillars or walls.

2. I claim the making of the beams for the floors, and the rafters for the roof by 30 bending a certain number of the parallel bands which have been used in the perpendicular walls below, to the required position to serve as beams and rafters, the same being strongly riveted or screwed together. 35

3. I claim the vertical continuous beam, Fig. 4, constructed of several parallel plates strongly riveted together, and also the combination of the horizontal and vertical beam of parallel plates, as shown in Figs. 1 and 2. 40

BERNARD JOACHIM LA MOTHE.
